IRONING MACHINE CLUTCH ASSEMBLY

Loren E. Schrader, Mount Clemens, Mich., assignor to Ironrite Inc., Mount Clemens, Mich., a corporation of Michigan

Application October 3, 1956, Serial No. 613,750

12 Claims. (Cl. 38—59)

This invention relates generally to ironing machines and more particularly to an ironing machine clutch assembly.

Ironers now in common use include a stationary shoe provided with heating elements and a rotatable roll mounted for controlled movement into and out of operative engagement with the shoe. For home use, the ironer must be capable of performing the usual ironing operations, namely, pressing and ordinary ironing. An in-and-out ironing operation is also desirable under certain circumstances. In pressing, the roll is maintained in a non-rotating position against the shoe for the required pressing period. In ironing, the roll is moved against the shoe with the roll rotating and the material to be ironed is fed between the roll and the shoe. An in-and-out ironing operation is required for material such as ruffled curtains which cannot be continuously moved between the roll and the shoe by rotation of the roll because of the bulk of the ruffles. The ironer is thus operated in an in-and-out ironing operation so that the roll automatically moves back and forth against the shoe and rotates when against the shoe. This invention provides a clutch assembly for an ironer which is capable of automatically and selectively providing the above ironing operations.

An object of this invention, therefore, is to provide an improved ironer clutch assembly.

A further object of this invention is to provide a clutch assembly which includes, as an integral part thereof, an actuating trigger so that the assembly can be checked for functional defects prior to its assembly in the ironer.

Another object of this invention is to provide a clutch assembly having parts which are efficiently cast from powdered metal.

A further object of this invention is to provide an ironing machine clutch assembly which is readily assembled in an ironing machine for adapting the machine for the desired ironing operations.

Another object of this invention is to provide a clutch assembly which is adapted to be installed in either a single or a double knee control ironing machine.

Yet another object of this invention is to provide an ironing machine clutch assembly which is relatively simple in construction, economical to produce and efficient in operation in providing the desired ironing operations.

Further objects, features and advantages of this invention will be apparent from a consideration of the following description when taken in connection with the accompanying drawing in which:

Fig. 1 is a side elevational view of an ironing machine, with the supporting legs therefor removed;

Fig. 2 is an enlarged sectional view of the ironing machine of this invention looking substantially along the line 2—2 in Fig. 1;

Fig. 3 is an enlarged fragmentary horizontal sectional view as seen along the line 3—3 in Fig. 1;

Fig. 4 is a sectional view looking along the line 4—4 in Fig. 3;

2

Fig. 5 is a fragmentary sectional view looking substantially along the line 5—5 in Fig. 3;

Fig. 6 is a side elevational view of the clutch assembly of this invention and the driving gear therefor removed from the ironer and showing the clutch assembly in a disengaged position;

Fig. 7 is a fragmentary vertical sectional view through the gear box for a double knee control ironer provided with the clutch assembly of this invention;

Fig. 8 is a side elevational view like Fig. 6 with some parts broken away and other parts shown in section for the purpose of clarity and illustrating the clutch assembly of this invention in driven engagement with the driving member therefor;

Fig. 9 is a fragmentary vertical sectional view through the gear box for a single knee control ironer provided with the clutch assembly of this invention and taken along a line in a single knee control ironer corresponding to the line 9—9 in Fig. 3;

Figs. 10 and 11 are composite diagrammatic views of parts of the clutch assembly of this invention, illustrating the changed positions of the parts during clutch operation and showing the relative positions of the trigger ring, cam ring and key elements in fragmentary developed plan form for both of the illustrated changed positions;

Fig. 12 is an exploded perspective view of the parts of the clutch assembly of this invention illustrated in Figs. 10 and 11; and

Figs. 13, 14 and 15 are composite diagrammatic views of parts of the clutch assembly of this invention and a single knee control rod therefor, illustrating the changed positions of the parts and the rod during clutch operation and showing the relative positions of the trigger ring, cam ring and key elements in fragmentary developed plan form for the changed positions.

With reference to the drawing, the clutch assembly of this invention, indicated generally at 20, is illustrated in Fig. 2 in assembly relation with an ironing machine 21. As best appears in Fig. 1, the machine 21 includes a main frame, only the table portion 22 of which is illustrated, and a stationary shoe 23 provided with internal heating elements, not shown, supported at what will hereinafter be referred to as the front or operator side 24 of the table 22. Arranged centrally on the table 22 at the rear side 26 thereof, is a housing 27, which rotatably supports a tube 28 (Fig. 2) extended lengthwise of the table 22. At its ends, the tube 28 carries a pair of upwardly and forwardly inclined arms 29 and 31 provided intermediate their ends with bearings 32 and 33 which rotatably support stub shafts 34 and 36, respectively, carried by opposite ends of the ironer roll 37.

An electric motor 38 (Fig. 2) on one side of the housing 27 acts through a first gear train 39 to drive a gear 41 in housing 27, which in turn acts through a selectively operable clutch mechanism 42 to drive a second gear train 43 connected to a shaft 44 extended axially of the tube 28. The shaft 44 in turn drives a third gear train 46 located in the arm 31 and operable to drive the stub shaft 36 for rotating the roll 37.

As best appears in Fig. 3, the gear 41 driven by the motor operated gear train 39 is provided with a hub extension 47 and is rotatably supported on a shaft 48 carried by the housing 27. Rotatably supported on the shaft 48 at a position adjacent the hub extension 47 is an irregular shape body member 49 (Figs. 3 and 12) for the clutch assembly 20. Keyed to an end portion 51 of the clutch body 49 remote from the hub extension 47 is a cam member 52 which cooperates with a follower roller 53 (Fig. 7) to raise and lower a leaf spring arm 54 extended rearwardly from the tube 28. On rotation of the cam 52 to a position in which the enlarged portion 50 thereof engages the follower 53, the arm 54 acts to rotate the

tube 28 in a counterclockwise direction as viewed in Fig. 7 to move the roll 37 downwardly into operative engagement with the shoe 23. Similarly, when the cam 52 is moved to a position in which the roller 53 is on the cam reduced portion 55, the arm 54 is lowered to rotate the tube 28 to provide for an upward movement of the roll 37 to an up position spaced from the shoe 23 and illustrated in Fig. 1. The follower 53 is maintained in rolling engagement with the cam 52 by an encircling strap (not shown).

The clutch assembly 20 is operable to provide for movement of the cam 52, by the driving gear 41, to a first stop position in which the reduced portion 55 of the cam engages the follower 53, a second stop position in which the enlarged portion 58 of the cam engages the follower, and to provide for continuous rotation of the cam. The assembly 20 includes the clutch body 49 which is of a generally tubular shape, having an axial bore 56 through which the shaft 48 extends. On its outer surface, the clutch body 49 (Fig. 12) is of a substantially stepped formation having the successively enlarged sections 57, 58 and 59 arranged inwardly of the reduced end portion 51, with the portion 59 being at the end 60b of the body 49 adjacent the hub extension 47. At diametrically opposite portions thereof, the body 49 is provided with a pair of longitudinally extended channels 61 of a depth to extend through the sections 57, 58 and 59. Slideably positioned within the channels 61 are a pair of key elements 62 and 63, each of which is provided at its opposite ends with lateral projections 64 and 66 which, for convenience of description, will hereinafter be referred to as the head and tail key portions, respectively. The keys 62 and 63 are of a length (Figs. 3 and 6) such that when positioned in the channels 61 with the head portions 64 positioned outwardly of and adjacent to the inner ends of the channels 61, the tail portions 66 are within the opposite ends of the channels 61.

Positioned about the body section 57 is a cam ring 67, integrally formed with a radially extended leg 68, having a lower half portion 69 corresponding substantially to the width of the body section 57. The upper half portion 71 is of a reduced width and constitutes slightly more than one-half of the ring 67 for a purpose to appear later. At one juncture of the portions 69 and 71, the cam ring 67 has a sharply inclined portion 72. At the other juncture of the portions 69 and 71, the ring 67 is provided with a gradually inclined cam surface 73. As will more clearly appear hereinafter, the cam ring portion 69 constitutes a cam means which acts to maintain the key heads 64 outwardly of the channels 61.

Rotatably mounted on the body section 58 is a trigger ring 74 (Fig. 12) of a width to extend about the cam ring 67 and provided with a first relatively deep peripherally extended cutout portion 76 through which the leg 68 extends. A pair of narrower cutout portions 77 extend in opposite directions from the cutout 76, with one cutout terminating in an inclined surface 78 and the other in a straight surface 79 hereinafter referred to as the "drop off surface." At diametrically opposite portions, substantially opposite the surfaces 78 and 79, the trigger ring 74 is provided with a pair of outwardly extended ears 65 and 70. Each ear includes a pair of rounded converged portions 75 positioned on vertically opposite sides of an enlarged slot 80 which is undercut relative to the ear portions 75. A retainer disc 90 is arranged on the body portion 51 against the section 57 to maintain the rings 67 and 74 on the body 49. A disc 90 has a pair of notches 95 positioned opposite the channels 61. A sleeve 100 on the portion 51 maintains the cam 52 and the disc 90 in a fixed spaced relation, with the cam 52 being press fit on the body portion 51 to maintain the disc 90 in a fixed position.

The leg 68 on the cam ring 67 extends upwardly through the cutout trigger ring portion 76 and is held in a

fixed upright position by a first plate member 81 extended transversely of the ring 67 and secured by a bolt 82 to a portion of the housing 27 (Figs. 3, 5 and 6). A second plate 83 arranged above the plate 81 and similarly held in a fixed position by the bolt 82 carries a yoke shape spring plate 84 having a pair of curved leg portions 86 and 88 extended partially about the shaft 48 for the clutch assembly 20. The combined length of the legs 86 and 88 (Fig. 5) is such that the head 64 of one or the other of the keys 62 and 63 is always engaged by the plate 84 during rotation of the clutch assembly. Also, the terminal end 87 of the longer leg 88 is outwardly curved to provide for the gradual engagement thereof with a key 62 or 63 moving under the terminal end 87 for engagement with the leg 88. The plate 84 acts, therefore, to continuously urge one or the other of the keys 62 or 63 to a position projected outwardly of the end 60b of the clutch body 49. Whether a key is free to move in its channel 61 to such a projected position or not depends on the position of the trigger ring 74, as will more clearly appear hereinafter.

As illustrated in Fig. 7, in the double knee control ironer a projection 91 on the upper end of a control rod 92 supported for vertical movement in a boss 93 on the housing 27, is positioned within the slot 80 in the ear 65 on one side of the trigger ring 74. The lower end of the rod 92 is connected through a link 94 to a knee pad (not shown) positioned beneath the ironer table 22 for convenient knee actuation by the ironer operator. A spring 96 extended between a portion 97 of the housing 27 and a retainer disc 98 on the link 94 normally maintains the trigger ring 74 in the position shown in Figs. 7 and 11. In this position (Fig. 11), the trigger ring 74 acts to hold the key 63 in a retracted position against the pressure of the spring plate 84 and the ring cut out portion 76 is arranged so that the end 89 thereof is positioned adjacent the cam ring leg 68. The half portion 69 of the cam ring 67 maintains the key 62 in a retracted position. For convenience of description, it is hereinafter assumed that the key 63 is adjacent the spring leg 88 and the key 62 adjacent the spring leg 86 in the up position of the roll 37 and vice versa in the down position of the roll 37 against the shoe 23.

On movement by the operator of the knee pad for the control rod 92, the rod 92 is moved upwardly against the action of the spring 96 to rotate the trigger ring 74 in a clockwise direction as viewed in Fig. 7 to the position of the trigger ring shown in Fig. 10, in which the opposite end 99 of the cut out portion 76 is adjacent the cam ring leg 68. The shape of the ear 65 to provide the two rounded converging portions 75 facilitates such movement of the control rod 92 without any binding of the ear 65 on the rod projection 91.

In the Fig. 10 position of the trigger ring 74, the drop off surface 79 has been moved behind or to one side of the key 63 so that the key 63 is opposite one cutout ring portion 77 and is thus free to move inwardly of its channel 61 to a projected position received in a notch 101 in the hub extension 47 for the driving gear 41. As a result, a driving connection is effected between the driving gear 41 and the cam 52, so that the cam 52 is rotated to move the ironer roll 37 relative to the stationary shoe 23. As long as the trigger ring 74 is maintained in this position illustrated in Fig. 10, every time a key 62 or 63 travels off the trigger ring 74 at the drop off surface 79, the leg 88 of the spring plate 84 acts to move the key into a cutout portion 77 of the trigger ring 74 to a position projected outwardly of the clutch body 49. Concurrently, the other key 62 or 63 is moved by the cam surface 73 on the cam ring 67 to a retracted position in its channel 61. This key is then maintained in a retracted position by the wide portions of the rings 67 and 74 until such key travels past the drop off surface 79. As previously described, the wide portions of the rings are of a size such that they are effective to engage only one of

the keys at one time. As a result, as long as the operator maintains the trigger ring 74 in the Fig. 10 position, a driving connection for the cam 52 is provided.

When the operator releases the knee pad, the spring 96 provides for a return of the control rod 92 to its downwardly moved position illustrated in Fig. 7 and a consequent movement of the trigger ring 74 in a counterclockwise direction to a position in which the ring 74 is returned to the position illustrated in Fig. 11. In this position, the ring 74 operates to maintain a key 62 or 63 in a retracted position after travel of the key off the wide ring portions. As a result, both keys 62 and 63 are maintained in retracted positions by the rings 67 and 74 so that the rotation of the cam 52 and the roll 37 is stopped.

In this connection, assume that the cam 52 is in a position in which the low side 55 is against the follower 53 so that the roll 37 is in an up position spaced from the shoe 23 as shown in Fig. 1. When the operator moves the control rod 92 upwardly and quickly releases the rod 92, by actuation of the corresponding knee pad, the key 63 is moved by the spring plate leg 88 to a projected position in which the tail portion 66 thereof is received in a notch 101 in the hub 47 to provide for rotation of the clutch body 49 in a counterclockwise direction as viewed in Figs. 5 and 12 to a position in which the engaged key is moved to a retracted position by the cam surface 73.

As best appears in Fig. 12, the inner sides of the key heads 64 are formed with angularly related surfaces 60. These surfaces 60 are related to the cam surface 73 on the cam ring 67 such that a key head 64 engages the cam surface 73 only at the juncture 60a of the surfaces 60. During travel of a key head 64 on the surface 73 when the juncture 60a reaches a "pull out point" intermediate the ends of the surface 73 the key is retracted. The position of the cam ring 67 is initially adjusted such that in the position of the trigger ring 74 illustrated in Fig. 11, the drop off surface 79 is spaced from the pull out point on the cam surface 73 a distance necessary to provide for movement of one of the keys through an angle of 180° in response to actuation and release of the knee pad for the control rod 92.

During rotation of the clutch body 49 in response to engagement of the key 63 with the hub 47, the rings 67 and 74 act to prevent the key 62 from being moved to a position engaged with the hub 47, since on release of the control rod 92 the trigger ring 74 is moved by the rod 92 in the direction of rotation of the body 49. The key 62 does not reach the drop off surface 79 before the key 63 reaches the pull out point on the cam surface 73. As a result, the cam 52 rotates only 180° to a position in which the high side 50 thereof engages the follower 53 so that the roll 37 is moved against the shoe 23. To return the roll 37 to an up position, it is only necessary to repeat the above step of tripping the control rod 92. The engagement of the key 62 with the hub 47 then provides for another 180° rotation of the cam 52. The arrangement of the end 105 of the spring plate leg 86 (Fig. 5) adjacent the key 63 in the down position of the roll 37 positively prevents any tendency of the cam 52 to rotate in an opposite direction under the action of the follower 53 (Fig. 7) to maintain the roller 37 against the shoe 23.

It is seen, therefore, that actuation of the control lever 92, which is located on one side of the trigger ring 74, controls the movement of the roll 37 relative to the shoe 23. A second control lever 104 (Figs. 3, 4 and 7) is mounted on the opposite side of the trigger ring 74 and is operable to actuate the clutch mechanism 42 (Fig. 2) and thus control rotation of the roll 37.

The clutch mechanism 42 (Fig. 3) includes a clutch gear 106 having teeth 107 formed on the side thereof opposite the driving gear 41. The gear 106 and an adjacent annular member 108 form an integral body unit,

generally designated 109, which is splined on the hub 111 for a driving gear 112 in the gear train 43 which drives the shaft 44. The gear 112 is mounted for free rotation on the shaft 48. A slot 113 separates the clutch gear 106 and the annular member 108 which is formed with sloping serrations 114 on the side thereof opposite the gear 106 for a purpose to appear later. Extended into the slot 113 is the bifurcated working end portion 116 of a clutch actuating fork 117 which has its opposite end mounted on a bar 118 slideably supported in bosses 119 and 121 on the housing 27. The working end portion 116 has lateral projections 122 extended from one side thereof for engagement with one side of the gear 106, and a dimple 123 projected from the opposite side for engagement with the serrations 114 to facilitate operation of the fork 117 to move the body unit 109 toward and away from the gear 41.

A spring 124, positioned about the bar 118 and extended between the boss 121 and the fork 117, which is held in an adjusted position on the bar 118 by a sleeve 126, biases the fork and the bar 118 in a clutch engaging direction. The bar 118 is projected through the boss 119 and terminates in a rounded end portion 127 positioned in engagement with an upper portion 128 (Figs. 4 and 7) of the upright control rod 104.

The portion 128 is of a gradually decreasing diameter in a downward direction so that as a result on upward movement of the rod 104 to a position in which the bar end 127 is opposite the reduced diameter section of the control rod portion 128, the bar 118 is moved by the spring 124 inwardly of the rod 104 on the portion 128 to a position corresponding to a clutch engaging position of the gear 106. A spring 129 for the rod 104 normally maintains the rod 104 in such upwardly moved position. On the other hand, when the control rod 104 is moved downwardly, against the pressure of the spring 129 and in response to operator pressure on a second knee pad (not shown) connected to the rod 104, the bar end 127 is moved outwardly of the rod 104 on the rod portion 128 against the action of the spring 124. The fork 117 is thus moved to the right as viewed in Figs. 3 and 4 to move the clutch body 109 in the same direction and disengage the gear 106 from the driving gear 41.

In response to disengagement of the clutch gear 106 and the driving gear 41, rotation of the roll 37 is stopped. On release of pressure on the knee pad associated with the control rod 104, the spring 124 provides for a prompt engagement of the clutch gear 106 with the driving gear 41 so that rotation of the roll 37 is resumed.

As best appears in Figs. 3 and 7, the terminal end portion 151 of the leaf spring arm 54 is positioned directly above the control rod 104. As a result, on downward swinging movement of the arm 54 in response to travel of the follower 53 on the low side 55 of the cam 52, the arm portion 151 acts to depress the control rod 104 a distance necessary to disengage the clutch mechanism 42. Consequently, when the roll 37 is in an up position, spaced from the shoe 23, the roll 37 is not rotating.

In the operation of the double knee control ironer (Fig. 7), assume that the ironer is in the inoperative position illustrated in Fig. 1 in which the roll is spaced from the shoe 23. In this position of roll 37, the arm 54 maintains the control rod 104 in a depressed position in which the clutch gear 106 is disengaged from the driving gear 41 so that the roll 37 is not rotating. Assume further that an ordinary ironing operation is desired. The operator exerts pressure on the knee pad corresponding to the control rod 92 to move the trigger ring 74 from the position shown in Fig. 11 to the position shown in Fig. 10. This knee pressure is then quickly released to provide for a quick return, under the action of the spring 96, of the trigger ring 74 to its Fig. 11 position. As previously described, in response to such movement of the trigger ring 74, the cam 52 rotates 180° to a position in which the arm 54 is operated to move

the roll 37 against the shoe 23. The arm 54 also releases the control rod 104 so that the spring 129 therefor moves the rod 104 upwardly to provide for engagement of the clutch gear 106 with the driving gear 41 by the spring 124 to rotate the roll 37.

The material to be ironed is then fed between the roll 37 and the shoe 23, with the rotation of the roll 37 providing for a continuous travel of the material. When the ironing operation is completed, the operator again actuates and quickly releases the knee pad corresponding to the control rod 92 so that the cam again rotates through an angle of 180° to return the roll 37 to its initial non-rotating position spaced from the shoe 23. In an ordinary ironing operation, no pressure is exerted on the knee pad corresponding to the control rod 104 since rotation of the roll 37 is desired and pressure on such knee pad is operable only to stop rotation of the roll 37.

Assume next that a pressing operation is desired. The knee pad for the control rod 104 is pressed to prevent rotation of the roll 37 and pressure on this knee pad is continuously maintained so that no driving force is provided for the roll 37. The material to be pressed is then placed against the shoe 23 and the other knee pad is pressed and quickly released, as described above, so that the roll 37 is moved against the shoe 23. When the roll 37 has been in this stationary position against the shoe 23 for the desired pressing period, the knee pad corresponding to the control rod 92 is again actuated to provide for a return movement of the roll to a position spaced from the shoe. This procedure is repeated until the desired pressing operation has been completed.

When an in-and-out ironing operation is desired, for ironing ruffles on a curtain or the like, rotation of the roll 37 when against the shoe 23 is desired so the knee pad corresponding to the control rod 104 is never actuated. The operator exerts pressure on the knee pad corresponding to the control rod 92 so that the trigger ring 74 is moved to its position shown in Fig. 10. This pressure is maintained so that the cam 52 continues to rotate, with first one key 63 and then the other key 62 being moved to a projected position engaged with the hub extension 47. The roll 37 is thus continuously moved toward and away from the shoe 23. Concurrently with this roll movement, the ruffled material is manually adjusted by the operator during the times the roll 37 is spaced from the shoe 23 until the ironing operation has been completed, at which time the knee pad corresponding to the control rod 92 is manipulated to return the roll 37 to its initial up position.

One of the main advantages of the clutch assembly 20 of this invention is that in addition to providing the desired operation of an ironer having a double knee control, the assembly 20 is also adapted for use in a single knee control ironer. As illustrated in Fig. 9, a pin 133, secured to and extended radially of a single upright control rod 132 corresponding to the control rod 104 illustrated in Fig. 7, is extended to a position within the slot 80 for the ear 70 on the trigger ring 74. The control rod 132 (Figs. 13, 14 and 15) has a recess 131 formed with a surface 134 inclined downwardly and inwardly of the control rod 132 for coaction with the end 127 of the clutch mechanism control bar 118. When the end 127 of the bar 118 projects fully into the recess 131 (Fig. 13), the clutch mechanism 42 is engaged, as previously described, and when the end 127 is moved outwardly of the recess 131 (Figs. 14 and 15), the clutch mechanism 42 is disengaged.

The control rod 132 is normally biased to an upper position (Fig. 13) by a spring (not shown) and is operable by a knee pad, which is also not shown, arranged beneath the table 22. In this position of the control rod 132, hereinafter referred to as an ironing position, the keys 62 and 63 are in retracted positions so that no drive is provided for the cam 52. In other words, if the cam 52

is in a position in which the roll 37 is rotating and is against the shoe 23, this position of the roll is maintained with the control rod 132 in the position illustrated in Fig. 13.

5 On actuation of the knee pad, the control rod 132 is movable downwardly to an intermediate or press position in which the end 127 of the clutch actuating bar 118 is moved by the inclined recess surface 134 outwardly of the recess 131 a distance providing for a disengagement 10 of the clutch mechanism 42. Such movement of the control rod 132 moves the pin 133 downwardly to in turn provide for a clockwise rotation of the trigger ring 74, as viewed in Figs. 13 and 14. However, such movement of the trigger ring 74 does not affect the position of the roll 37 since the drop off surface 79 remains ahead of the key 62 and the trigger ring 74 maintains the key 62 15 in a retracted position. The press position of the control rod 132 corresponds to a position to which the rod 132 is depressed by the arm 54 each time the roll 37 is moved to 20 its up position by rotation of the cam 52 to a position in which the low side 50 thereof engages the follower 53.

On actuation of the knee pad to further move the rod 132 in a downward direction to a lower position, herein-after described as the trip position, the end 127 of the bar 118 is moved entirely out of the recess 131. Such movement of the bar 118, however, has no effect on the roll 37 since the clutch mechanism 42 is maintained in a disengaged position so that the roll 37 does not rotate. 30 On the other hand, the trigger ring is further rotated in a clockwise direction to a position (Fig. 15) in which the drop off surface 79 is behind the key 62, so that the key 62, under the action of the spring leg 88, is moved to an extended position to provide for rotation of the cam 52. If the knee pad is then quickly released, the cam 35 52 rotates 180° to change the position of the roll 37 relative to the shoe 23.

In the operation of an ironer having a single knee control rod 132, assume that the roll 37 is in an up position 40 spaced from the shoe 23. In this position of the roll 37, the arm 54 maintains the control rod 132 in a press position (Fig. 14) in which the clutch actuating bar 118 disengages the clutch mechanism 42. Also, in this position of the roll, the key 63 is in the position illustrated 45 for the key 62 in Fig. 14. Assume further that an ordinary ironing operation is desired. The knee pad for the control rod 132 is actuated to move the rod 132 downwardly to the trip position (Fig. 15) in which the key 63 is moved inwardly to an engaged position with the hub 50 47 to provide for rotation of the cam 52. The knee pad is then quickly released to provide for return of the rod 132 to the ironing position and limit rotation of the cam 52 to 180°.

The roll 37 is thus moved against the shoe 23 and rotated since the end 127 of the bar 118 is within the recess 131. When the ironing operation is to be terminated, the control rod 132 is again moved to its trip position (Fig. 15) and released to provide for the return of the roll 37 to its non-rotating up position.

60 If a pressing operation is desired, the control rod 132 is first moved to its trip position (Fig. 15) and then released for movement only to the intermediate press position. For this manipulation of the control rod 132, the trigger ring 74 is actuated to provide for a 180° rotation of the cam 52 to move the roll 37 against the shoe 23. However, the bar 118 is maintained in a position 65 out of the recess 131 (Fig. 14) so that no rotation of the roll 37 is provided.

70 It can thus be seen that the clutch assembly 20 is readily assembled with a single knee control rod 132 to provide for ironer operation in response to movement of the rod 132 between three predetermined positions. With the single knee control rod 132 the ironer is capable of the usual ironing and pressing operations. An 75

in-and-out ironing operation cannot be accomplished with the single knee control rod 132.

From the above description, it is seen that this invention provides an ironing machine clutch assembly 20 which is readily operable in conjunction with the clutch mechanism 42 which controls rotation of the roll 37 to provide the desired ironing operations. The cam and trigger rings 67 and 74, respectively, are readily and accurately cast of powdered metal within the required tolerance limits to thus eliminate the precise machining operations normally required in the construction of clutch assemblies. Furthermore, by virtue of the movement of the rings 67 and 74 in planes perpendicular to the plane of the shaft 48, the tolerance buildups of the elements extended longitudinally of the shaft 48 are not enlarged by the tolerances permitted on the rings 67 and 74. As a result, greater tolerance latitude is permitted in the construction of the parts on the shaft 48.

By virtue of the unit construction of the assembly 20, as it appears in Figs. 6 and 8 in assembly with the gear 41, the assembly 20 is readily checked for proper operation prior to its assembly in an ironing machine, thus eliminating the necessity for removing a defective clutch assembly 20 from a finished machine. Further, since the trigger ring 74 is initially formed with the two oppositely extended ears 65 and 70, it is readily assembled in either a double knee control machine (Fig. 7) or a single knee control machine (Fig. 9).

Although the invention has been described with respect to a preferred embodiment thereof, it is to be understood that it is not to be so limited, since changes can be made therein which are within the scope of this invention as defined by the appended claims.

What is claimed is:

1. In an ironing machine having a main frame, a shoe mounted in a fixed position on the frame, a rotatable roll movably mounted on the frame for movement into and out of engagement with the shoe, and motor means on said frame for both rotating and moving said roll; cam means operatively associated with said roll for moving the roll toward and away from said shoe on rotation of said cam means, clutch means operatively arranged between said motor means and said cam means for providing selective rotation of said cam means, said clutch means comprising a rotatable clutch body arranged in a driving relation with said cam, a pair of key members slidably mounted on spaced portions of said body for movement to positions projected outwardly of one end thereof, means for continuously biasing one or the other of said key members toward said projected position, a stationary cam ring positioned about said clutch body, cam means on said cam ring engageable with said key members, said cam means being of a size to continuously engage one or the other of said key members to retract the engaged key member against the pressure of said biasing means, a trigger ring positioned about said cam ring and selectively movable between a pair of rotated positions relative thereto, in one of said positions said trigger means being engaged with one of said key members to maintain said member in a retracted position and in the other position being in a clearance relation with both of said key members to provide for movement of one of said key members to a projected position, and a key receiving member positioned opposite said one end of the clutch body and arranged in a driven relation with said motor means for driving said clutch body when one of said key members is received in said key receiving member.

2. For use in an ironing machine having a shoe, a roll mounted for movement toward and away from said shoe, a cam operatively associated with said roll for moving the roll, and a motor for rotating said cam; a clutch assembly for selectively imparting rotary motion to said cam from said motor, said assembly comprising a cylindrical clutch body secured to said cam for rotation

therewith, a pair of key members slidably mounted on diametrically opposite portions of said body for movement to positions projected outwardly of one end thereof, means biasing said key members to said projected positions, a stationary cam ring positioned about said clutch body, cam means on said ring engaged with one of said key members for maintaining said one key member inwardly of a projected position, a trigger ring positioned about and rotatably supported on said cam ring, means biasing said trigger ring to a first position engaged with the other one of said key members for maintaining said other key member against movement to a projected position, said trigger ring being movable against the biasing means therefor to a second position in a clearance relation with said other key member for movement thereof to a projected position, and a key receiving member arranged in a driven relation with said motor and adapted to receive said key members when in the projected positions thereof for driving said clutch body from said motor.

3. In an ironing machine which includes a clutch assembly having a rotatable clutch body provided with key members slidably axially thereof and biased toward a position projected from one end thereof, a stationary cam ring positioned about said clutch body for selective engagement with said key members to move said key members inwardly of said projected positions, and a trigger ring positioned about said cam ring and movable between a pair of positions relative thereto, said trigger ring in a first position cooperating with said cam ring to maintain said key members inwardly of the projected positions thereof, and in a second position being in a clearance relation with said key members for movement of a key member to a projected position.

4. In an ironing machine which includes a clutch assembly having a rotatable clutch body provided with a pair of spaced key members slidably axially thereof and biased toward a position projected outwardly from one end thereof for engagement with a driving member, a stationary cam ring positioned about said clutch body for engagement with said key members, said cam ring being of a shape to provide for the movement of first one and then the other of said key members inwardly from said projected positions on rotation of said clutch body, a trigger ring positioned about said cam ring for selective movement between a pair of positions, said trigger ring being of a shape such that in one of said positions the trigger ring engages the one of said key members which is not maintained against movement to a projected position by said cam ring and acts to releasably prevent movement of said one key member to a projected position, said trigger ring being of a shape such that in a second position thereof said one key member is movable to the projected position therefor to provide for driving of said clutch body, with movement of said trigger ring from said second to said first position providing for movement of both said key members inwardly from said retracted positions to provide for interruption of driving of said clutch body in increments proportional to the spacing of said key members.

5. In an ironing machine having a main frame, an ironing shoe fixedly mounted on said main frame, an ironing roll movably mounted on said frame for movement into and out of engagement with said shoe and a driving member for moving said roll; clutch means for controlling said roll movement, said clutch means including a clutch body, key members on said clutch body movable into and out of driven engagement with said driving member, and a pair of coaxing relatively movable ring members mounted on said clutch body and operatively associated with said key members for controlling the movement thereof, said ring members being operable on relative movement thereof to provide selectively for movement of said roll into engagement with said shoe, out of engagement with said shoe, and for con-

tinuous back and forth movement into and out of engagement with said shoe.

6. In an ironing machine having a main frame, an ironing shoe fixedly mounted on said frame, a rotatable ironing roll movably mounted on said main frame for movement into and out of engagement with said shoe, and a driving member for rotating said roll and for moving the roll into and out of engagement with said shoe; a clutch assembly selectively operable to provide for movement of said roll into and out of engagement with said shoe, a clutch mechanism operable to start and stop rotation of said roll, said clutch assembly including a clutch body, key members on said body movable into and out of driven engagement with said driving member, a pair of coacting relatively movable ring members mounted on said clutch body and operatively associated with said key members for controlling the movement thereof into engagement with said driving member, actuating means engaged with one of said ring members operable to provide for said relative ring member movement, and means responsive in operation to said actuating means for selectively actuating said clutch mechanism to provide for rotation of said roll.

7. For use in an ironing machine having a shoe, a roll mounted for movement toward and away from said shoe, a cam operatively associated with said roll for moving the roll, and a motor for rotating said cam; a clutch assembly for selectively imparting rotary motion to said cam from said motor, said assembly comprising a cylindrical clutch body secured to said cam for rotation therewith, a pair of key members slidably mounted on diametrically opposite portions of said body for movement to positions projected outwardly of one end thereof, means operatively associated with said key members for alternately biasing one or the other of said key members toward a position projected outwardly of one end of said clutch body, a pair of relatively movable ring members positioned about said clutch body and engageable in one position thereof with said key members for preventing movement of the key members to said projected positions, said ring members in a second position thereof providing for movement of one of said key members to a projected position, and a key receiving member arranged in a driven relation with said motor and adapted to receive said key members when in the projected positions thereof for driving said clutch body from said motor.

8. In an ironing machine having a main frame, an ironing shoe fixedly mounted on said main frame, a rotatable ironing roll movably mounted on said frame for movement into and out of engagement with said shoe and a driving member for rotating said roll and for moving said roll into and out of engagement with the shoe; first clutch means for controlling said roll movement, second clutch means for controlling rotation of said shoe, a control rod movably mounted on said main frame for actuating said first clutch means, said control rod having a recess formed therein and provided with an inclined surface, and means including an actuating bar for said second clutch means biased toward a position projected into said recess and movable out of said recess along said inclined surface in response to axial movement of said control rod for actuating said second clutch means in a predetermined coordinated relation with actuation of said first clutch means.

9. For use in ironing machine having a shoe, a rotatable roll mounted for movement toward and away from said shoe, a cam operatively associated with said roll for moving the roll relative to the shoe, driving means for rotating said roll, a motor for rotating said cam and said roll, a clutch assembly for selectively imparting rotary motion to said cam from said motor, a clutch mechanism for selectively driving said roll driving means from said motor; said clutch assembly comprising a cylindrical clutch body secured to said cam for rotating

the cam, a pair of key members slidably mounted on diametrically opposite portions of said body for movement to positions projected outwardly of one end thereof, means biasing said key members to said projected positions, a stationary cam ring positioned about said clutch body, a trigger ring movably mounted on said clutch body for movement between a pair of positions, cooperating means on said rings for controlling the movement of said key members to the projected positions therefor, said rings in one position of said trigger ring providing for the maintaining of said key members inwardly of the projected positions therefor, and in a second position for alternate movement of said key members to projected positions, a key receiving member arranged in a driven relation with said motor and adapted to receive a key member in the projected position thereof for driving said clutch body from said motor, means for moving said trigger ring, manually operable actuating means for operating said clutch mechanism to provide for selective rotation of said roll and means responsive in operation to the position of said cam for operating said actuating means.

10. For use in an ironing machine having a shoe, a rotatable roll mounted for movement toward and away from said shoe, a cam operatively associated with said roll for moving the roll, and a motor for rotating said cam; a clutch mechanism for selectively imparting rotary motion to said roll, a clutch assembly for selectively imparting rotary motion to said cam from said motor, said assembly comprising a cylindrical clutch body secured to said cam for rotation therewith, a pair of key members slidably mounted on diametrically opposite portions of said body for movement to positions projected outwardly of one end thereof, means operatively associated with said key members for alternately biasing one or the other of said key members toward a position projected outwardly of one end of said clutch body, a pair of relatively movable ring members positioned about said clutch body and engageable in one position thereof with said key members for preventing movement of the key members to said projected positions, said ring members in a second position thereof providing for movement of one of said key members to a projected position, a key receiving member arranged in a driven relation with said motor and adapted to receive said key members when in the projected positions thereof for driving said clutch body from said motor, a reciprocally movable actuating member mounted on said frame and movably connected to one of said ring members for relatively moving the ring members and means responsive in operation to movement of said actuating member to operate said clutch mechanism.

11. In an ironing machine having a main frame, an ironing shoe fixedly mounted on said main frame, a rotatable ironing roll movably mounted on said frame for movement into and out of engagement with said shoe, a motor for rotating said roll and for moving the roll into and out of engagement with said shoe, a clutch assembly for selectively imparting movement to said roll from said motor, a clutch mechanism selectively operable to provide for rotation of said roll from said motor, said clutch assembly including a clutch body, a driving member driven from said motor, means movably mounted on said clutch body for movement into and out of driven engagement with said driving member, a pair of coacting relatively movable ring members mounted on said clutch body and operatively associated with said movable members for controlling the movement thereof into and out of engagement with said driving member to provide selectively for movement of said roll into and out of engagement with said shoe, first manually operable means for relatively moving said ring members, second manually operable means for selectively actuating said clutch mechanism, and means carried by said roll and engageable with said second manually operable means in a position

of said roll out of engagement with said shoe for operating said second means to disengage said clutch mechanism.

12. For use in an ironing machine having a shoe, a rotatable roll mounted for movement toward and away from said shoe, a cam operatively associated with said roll for moving the roll between a first position against the shoe and a second position spaced from the shoe, driving means for rotating said roll, a motor for rotating said cam and said roll, a clutch assembly for selectively imparting rotary motion to said cam from said motor, a clutch mechanism for selectively driving said roll driving means from said motor; said clutch assembly comprising a cylindrical clutch body secured to said cam for rotating the cam, a pair of key members slidably mounted on diametrically opposite portions of said body for movement to positions projected outwardly of one end thereof, means biasing said key members to said projected positions, a stationary cam ring positioned about said clutch body, a trigger ring movably mounted on said clutch body for movement between a pair of positions, cooperating means on said rings for controlling the movement of said key members to the projected positions therefor, said rings in one

position of said trigger ring providing for the maintaining of said key members inwardly of the projected position therefor, and in a second position for successive movement of said key members to projected positions so that one key member is moved to a projected position concurrently with the retraction of the other key member, a key receiving member arranged in a driven relation with said motor and adapted to receive a key member in the projected position thereof for driving said clutch body from said motor, means for moving said trigger ring, actuating means for operating said clutch mechanism to provide for selective rotation of said roll, means responsive in operation to the arrangement of said cam in the second position thereof for operating said actuating means to disengage said clutch mechanism and discontinue rotation of said roll, and means on said actuating means engaged with said trigger ring for moving the trigger ring between said positions therefor.
